Inventor:

Thomas Lyons

United States Patent Office.

THOMAS LYONS, OF HARTFORD, CONNECTICUT.

Letters Patent No. 80,983, dated August 11, 1868.

IMPROVEMENT IN DOOR-BELLS.

The Schedule referred to in these Letters Patent and making part of the same.

TO ALL WHOM IT MAY CONCERN:

Be it known that I, THOMAS LYONS, of Hartford, county of Hartford, and State of Connecticut, have invented certain new and useful Improvements in Call-Bells; and to enable others skilled in the art to make and use the same, I will proceed to describe its construction and operation, by referring to the drawings, in which the same letters indicate like parts in each of the figures.

The nature of this invention will be understood from the specification and drawings.

In the accompanying drawings—

Figure 1 is a face view of the actuating-mechanism, with the bell removed.

Figure 2 is a sectional edge view thereof.

a represents a door or wall, upon which the device is attached.

b is a plate, upon which the mechanism is arranged and secured.

c is a stud, secured in a central position on the plate *b*, to which the bell is secured, in the common way.

d are the hammers, (one or more, as desirable,) secured, by screws *e*, to studs *f*, which are thrown outward, and strike the bell, and return to rest by their own gravity.

g is an actuating-arm or plate, secured, by a screw, *e'*, to a stud, *f'*, and vibrates back and forth between, and actuates the hammers *d*.

h is a spindle-socket, secured or formed on the lower portion of the plate *b*, having a slit in its upper edge.

i is a head, fitted and secured to the inner end of the spindle *k*. On the upper side of this head *i*, is secured or formed an incline elevation, which acts upon the lower end of the arm *g*, so that when the spindle *k* is pulled forward by the knob *m*, the arm *g* will be thrown sideways in one direction, until the incline elevation passes the arm, when, by the force of the spring *n*, secured to the stud *f'*, the arm will react against one of the hammers, and cause it to strike the bell; and when the head *i*, with the spindle *k*, is reacted by means of the spring *o*, upon the knob-spindle *k*, taking its bearing, one end against said head, and the other against the bottom of the socket, the arm *g* will be thrown in the opposite direction, and again, by the reaction of the spring *n*, will throw the opposite hammer against the bell, the hammers each time returning to their resting-place by their own gravity.

Thus I am enabled to cheapen the manufacture, and produce a better and more efficient article for use.

What I claim, therefore, and desire to secure by Letters Patent, is—

The arm *g*, in combination with the incline elevation *i'*, on head *i*, and hammers *d*, arranged and operating substantially as and for the purpose described.

THOMAS LYONS. [L. S.]
